OSCAR P. OSTERGREN, OF BROOKLYN, NEW YORK, ASSIGNOR OF ONE-FOURTH TO
WILLIAM V. HIRSH, OF BROOKLYN, NEW YORK.

ROTARY ENGINE.

1,001,676.

Specification of Letters Patent. Patented Aug. 29, 1911.

Application filed August 29, 1910. Serial No. 579,478.

To all whom it may concern:

Be it known that I, OSCAR P. OSTERGREN, a subject of the Crown of Sweden, and a resident of Brooklyn, county of Kings, and 5 State of New York, have invented certain new and useful Improvements in Rotary Engines, of which the following is a specification, reference being had to the accompanying drawings, forming a part thereof.

10 My invention relates to rotary engines, and particularly to a type of rotary engines in which two or more rotary co-acting elements are arranged side by side in parallel relation and are provided with co-en- 15 gaging complementary abutments and recesses.

My invention consists, first, in a novel form of engine in which a plurality of rotating elements each combine and co-act 20 with a single central rotary element around which they are disposed; and second, to a novel form, construction, and arrangement of valve mechanism for admitting motive fluid to the rotating elements, including a 25 novel form and construction of means for varying the point of cut-off of the motive fluid.

My invention also consists in many novel 30 details of construction and combinations of parts, such as will be pointed out more fully hereinafter, and in order that my invention may be thoroughly understood, I will now proceed to describe an embodiment thereof, having reference to the accompanying 35 drawings illustrating the same, and will then point out the novel features in claims.

In the drawings: Figure 1 is a view in central transverse section of an engine constructed in accordance with my invention. 40 Fig. 2 is a view in central vertical longitudinal section therethrough, the plane of section being indicated by the line 2-2 in Fig. 1. Fig. 3 is a longitudinal section therethrough upon the plane of the line 45 3-3 of Fig. 1. Fig. 4 is a detail central transverse sectional view of certain parts of the engine showing the parts as adjusted to different positions from those in which they appear in Fig. 1. Fig. 5 is a view in 50 part end elevation and part transverse section through the gear connections of the rotary impelling elements of the engine. Fig. 6 is a detail view in part side elevation and part longitudinal section of the main

rotating element showing particularly the 55 details of the valve means employed.

The engine, in general, comprises a main casing 10 having a central cylindrical bore 11 and a plurality of smaller bores 12 disposed around the same in parallel relation 60 therewith. The bores 12 overlap the central bore 11 whereby they communicate laterally with each other, as will be readily understood by reference to Fig. 1 of the drawings. End heads 13 and 14 secured 65 to the said casing and forming in fact a part thereof, serve to close in part the bore openings through the casing portion 10, individual supplemental end heads 15 being conveniently provided as removable portions 70 of these end heads 13 and 14 at the ends of the small bores 12, whereby access may be readily had thereto without the necessity of removing the main end heads 13 or 14. The casing member contains in 75 addition to the bores 11 and 12 a gear chamber 16 arranged to the rear thereof and divided from the bores by means of a partition 17. Rotatively mounted in the bore 11 is a rotating element comprising a head 80 18; the said head is mounted upon the main drive shaft 19, one of the bearings therefor being disposed in the end head 14. This head 18 is generally of cylindrical form in outer contour and is disposed concentri- 85 cally within the said bore 11, being, how- ever, of smaller diameter than the bore whereby a substantially annular space 20 is formed between the outer periphery of the said head and the inner walls of the said 90 bore. The said head is provided with a plurality of abutments 21,—four in the present instance,—which extend across this annular space and engage the inner walls 95 of the said bore.

Mounted in each of the bores 12 is a head 22. The diameter of these heads is less than that of the diameter of the bores 12, but is such that the peripheries thereof are in rolling contact with the periphery of the 100 head 18. The diameter, moreover, of these smaller heads 22 is just one-quarter of that of the main head 18 whereby, when a true rolling contact between the heads is main- 105 tained, the said smaller heads will rotate four times for each revolution of the main head. Each of these small heads 22 is pro- 110 vided with an abutment 23, corresponding

to the abutments 21 of the main head, and the main head and smaller heads are each provided with complementary recesses 24—25, those of the main head being arranged 5 to receive the abutments 23 of the small heads in their rotation, and those of the small heads being arranged to receive the abutments 21 of the main head.

The several heads are connected together 10 so that they will rotate at the proper relative speeds, by means of suitable gearing comprising a spur gear 26 secured to the main head 18 and pinions 27 secured to the smaller heads 22 respectively. These gears 15 are contained in the gear chamber 16 above referred to, the shafts of the several heads being arranged to extend through the said gear chamber for this purpose.

The head 18, the outer portion of which is 20 of ring-like form, is provided through this ring-like portion with a plurality of motive fluid admission channels 28 whereby motive fluid admitted to the interior of the head will pass through these passages into the 25 annular motive fluid chamber 20 just to the rear of each of the abutments 21. Mounted within the ring-like portion of the head 18 is a valve means by which these passages 28 may be closed after they have been opened 30 for a certain time, whereby the motive fluid may thereafter be employed expansively; and I also preferably provide means, as will presently be explained, for varying the point at which the motive fluid may be thus 35 cut off. The valve means comprises a stationary portion which includes a plurality of segments 29 conveniently secured fast to, or formed as a part of, the end head 18, and a relatively adjustable part 30 carried by a 40 shaft or spindle 31. The part 30 is mounted within a chamber 40 within the central portion of the end head 18, the chamber being closed by an auxiliary cover plate 41; the auxiliary cover plate 41 contains 45 a bearing for the spindle 31, as will be seen by reference to Fig. 3. This relatively movable part 30 includes abutments 32 which form substantially extensions of the segments 29, and flanges 33 to 50 which the said abutments are connected upon their inner faces at the rear end of the said flanges, the inner faces of the segments 29 being in sliding engagement with the outer faces of the said flanges 33 throughout the remaining portion thereof.

Referring to Fig. 1 and noting that the head 18 rotates in the direction of the arrow therein, it will be seen that motive fluid will be admitted to the passages 28 as each of 60 them passes the forward end of the segment 29 adjacent thereto, and it will also be seen that motive fluid will be continuously admitted through the said passages until the same pass the rear edges of the abutments

32. It will then follow that by adjusting the 65 abutments 32 rearwardly with respect to the segments 29, the flanges 33 preventing motive fluid from passing between the rear faces of the segments and the forward faces of the abutments, the extent of angular 70 movement of the head through which motive fluid will be admitted, will be reduced. To this extent the segments 29 act as a main steam valve and the adjustable abutments 32 75 as a rider cut-off valve, as these terms are commonly used in engine practice.

For the purpose of automatically varying the position of the adjustable portion 32—33 of the valve means, I have provided a centrifugal governor 34 driven by a belt connection 35 from the main shaft 19, and I have provided connections 36 from the said governor to the spindle or shaft 31 as will be readily understood by reference to the drawings. Thus, as the speed of the engine 85 increases beyond a certain point the valve means may be adjusted so as to reduce the period of motive fluid admission whereby a predetermined rate of speed may be maintained as is usual and desirable in engines 90 employing gases under pressure, such as steam, compressed air, and the like, as motive fluid.

I have provided for carrying away the 95 exhaust motive fluid from the various subdivisions of the annular chamber 20, the same comprising ports and passages 37 which conveniently connect with the several small bores 12 in proximity to the point at which the bores 12 meet the bore 11 at their 100 rear ends, *i.e.*, the ends first met by the abutments 21 in the direction in which the heads 18 are arranged to rotate as described above. By this arrangement the portions of the 105 annular chamber 20 in advance of each of the abutments 21 is constantly open to exhaust, while the portions to the rear of the said abutments constitute receiving and expansion chambers for the live motive fluid.

If desired the exhaust motive fluid may 110 go to one or more re-heaters 38, this being especially beneficial where the motive fluid is employed in a second stage as is common in compound engines. Motive fluid is admitted to the interior of the engine through 115 an inlet passage 39 (see particularly Fig. 2).

From the foregoing the operation of the engine will be readily understood. In general motive fluid admitted through the passage 39, passes to the center of the casing 120 and thence up through the valve means within the main head 18 against the inner wall of the ring-like portion of the head 18. As the motive fluid openings 28 in the head pass the forward edges of the segments 29, the motive fluid passes through these passages 28 into those portions of the annular chamber 20 which are located between the 125

rear faces of the abutments 21 and the peripheral surfaces of the heads 22. The peripheral surfaces of the heads 22 act as stationary abutments or walls for the motive fluid, the forward movable walls being the rear faces of the abutments 21, whereby the energy of the motive fluid is partially expended in forcing the head 18 around in the direction of the arrow in Fig. 1. In addition to the foregoing each of the small heads 22 act themselves as impelling members, those portions of the annular spaces between the periphery of the said heads and the inner walls of the bores 12 and to the rear 15 of the abutments 23 carried by the said heads acting as motive fluid spaces, the periphery of the main head 18 in this connection acting as the stationary abutment or wall for the motive fluid while the abutments 23 act as the movable walls. After the main head has moved through nearly one-quarter of a revolution and each of the auxiliary heads 22 have moved through nearly an entire revolution, the abutments 25 23 of the auxiliary heads 22 will have passed the exhaust ports 37 while the abutments 21 of the main head will also have passed the point at which the main and auxiliary bores join each other, whereby the spent motive 30 fluid from both the main head and the auxiliary heads will be discharged through the said exhaust passages.

From the foregoing it will be seen that the motive fluid acts not only upon the main head but also upon the auxiliary heads and that in a single revolution of the engine as a whole, there are no less than eight points at which the motive fluid is directly acting and imparting its energy for propulsive purposes. It will also be seen that so far as the central wheel is concerned the same is absolutely balanced, for the various pressures are applied uniformly at a plurality of points around the periphery thereof. The auxiliary heads 22 are not, however, completely balanced and as it is necessary to the efficient operation of an engine of this description that they be balanced as far as possible I refer to an application filed by me upon the 18th day of February, 1911, and serially numbered 608,212 which is pending herewith, as showing a means by which they may be so balanced.

What I claim is:

55 1. The combination with a casing having a main cylindrical bore therein and a plurality of supplemental cylindrical bores surrounding the central bore and in overlapping parallel relation therewith, of main and supplemental cylindrical rotating elements mounted concentrically in the said bores, and whose diameters are less than the bores containing them, the peripheries of the said main and supplemental rotating

elements being in rolling contact with each other, the said main and supplemental rotating elements being provided with complementary abutments and recesses for engagement with each other, the sum of the diameters of all the supplemental rotating elements being equal to the diameter of the main rotating element, and gearing for connecting the said main and supplemental rotating elements together. 65

2. The combination with a casing having a main cylindrical bore therein and a plurality of supplemental cylindrical bores surrounding the central bore and in overlapping parallel relation therewith, of main and supplemental cylindrical rotating elements mounted concentrically in the said bores, and whose diameters are less than the bores containing them, the peripheries of the said main and supplemental rotating elements being in rolling contact with each other, the said main and supplemental rotating elements being provided with complementary abutments and recesses for engagement with each other, the said main rotating element being hollow and arranged 70 to receive motive fluid therein, the peripheral wall thereof having a plurality of motive fluid passages therethrough one to the rear of each of the abutments therein, and gearing for connecting the said main and supplemental rotating elements together. 80

3. The combination with a casing having a main cylindrical bore therein and a plurality of supplemental cylindrical bores surrounding the central bore and in overlapping parallel relation therewith, of main and supplemental cylindrical rotating elements mounted concentrically in the said bores, and whose diameters are less than the bores containing them, the peripheries of the said main and supplemental rotating elements being in rolling contact with each other, the said main and supplemental rotating elements being provided with complementary abutments and recesses for engagement with each other, the sum of the diameters of all the supplemental rotating elements being equal to the diameter of the main rotating element, the said main rotating element being hollow and arranged 90 to receive motive fluid therein, the peripheral wall thereof having a plurality of motive fluid passages therethrough one to the rear of each of the abutments therein, and gearing for connecting the said main and supplemental rotating elements together. 95

4. The combination with a casing having a main cylindrical bore therein and a plurality of supplemental cylindrical bores surrounding the central bore and in overlapping parallel relation therewith, of main and supplemental cylindrical rotating elements mounted concentrically in the said 100

bores, and whose diameters are less than the bores containing them, the peripheries of the said main and supplemental rotating elements being in rolling contact with each other, the said main and supplemental rotating elements being provided with complementary abutments and recesses for co-engagement with each other, the said main rotating element being hollow and arranged to receive motive fluid therein, the peripheral wall thereof having a plurality of motive fluid passages therethrough one to the rear of each of the abutments therein, valve means located within the said hollow main rotating element for co-action with the said passages, and gearing for connecting the said main and supplemental rotating elements together.

5. The combination with a casing having
20 a main cylindrical bore therein and a plu-
rality of supplemental cylindrical bores sur-
rounding the central bore and in overlap-
ping parallel relation therewith, of main
25 and supplemental cylindrical rotating ele-
ments mounted concentrically in the said
bores, and whose diameters are less than the
bores containing them, the peripheries of
the said main and supplemental rotating
elements being in rolling contact with each
30 other, the said main and supplemental ro-
tating elements being provided with com-
plementary abutments and recesses for co-
engagement with each other, the sum of the
35 diameters of all the supplemental rotating
elements being equal to the diameter of the
main rotating element, the said main rotat-
ing element being hollow and arranged to
receive motive fluid therein, the peripheral
40 wall thereof having a plurality of motive
fluid passages therethrough one to the rear
of each of the abutments therein, valve
means located within the said hollow main
rotating element for co-action with the said
45 passages, and gearing for connecting the
said main and supplemental rotating ele-
ments together.

6. The combination with a casing having a main cylindrical bore therein and a plurality of supplemental cylindrical bores surrounding the central bore and in overlapping parallel relation therewith, of main and supplemental cylindrical rotating elements mounted concentrically in the said bores, and whose diameters are less than the bores containing them, the peripheries of the said main and supplemental rotating elements being in rolling contact with each other, the said main and supplemental rotating elements being provided with complementary abutments and recesses for engagement with each other, the said main rotating element being hollow and arranged to receive motive fluid therein, the peripheral wall thereof having a plurality of mo-

55
tive fluid passages therethrough one to the rear of each of the abutments therein, valve means located within the said hollow main rotating element for co-action with the said passages, means for adjusting the position of the said valve means with respect to the said passages, and gearing for connecting the said main and supplemental rotating elements together. 70

7. The combination with a casing having
a main cylindrical bore therein and a plu- 75
rality of supplemental cylindrical bores sur-
rounding the central bore and in overlap-
ping parallel relation therewith, of main
and supplemental cylindrical rotating ele-
ments mounted concentrically in the said 80
bores, and whose diameters are less than the
bores containing them, the peripheries of the
said main and supplemental rotating ele-
ments being in rolling contact with each
other, the said main and supplemental ro- 85
tating elements being provided with comple-
mentary abutments and recesses for co-en-
gagement with each other, the sum of the
diameters of all the supplemental rotating 90
elements being equal to the diameter of the
main rotating element, the said main rotat-
ing element being hollow and arranged to
receive motive fluid therein, the peripheral 95
wall thereof having a plurality of motive
fluid passages therethrough one to the rear
of each of the abutments therein, valve
means located within the said hollow main
rotating element for co-action with the said
passages, means for adjusting the position of 100
the said valve means with respect to the said
passages, and gearing for connecting the
said main and supplemental rotating ele-
ments together.

8. The combination with a casing having a main cylindrical bore therein and a plurality of supplemental cylindrical bores surrounding the central bore and in overlapping parallel relation therewith, of main and supplemental cylindrical rotating elements mounted concentrically in the said bores, and whose diameters are less than the bores containing them, the peripheries of the said main and supplemental rotating elements being in rolling contact with each other, the said main and supplemental rotating elements being provided with complementary abutments and recesses for co-engagement with each other, the said main rotating element being hollow and arranged to receive motive fluid therein, the peripheral wall thereof having a plurality of motive fluid passages therethrough one to the rear of each of the abutments therein, valve means located within the said hollow main rotating element for co-action with the said passages, means for adjusting the position of the said valve means with respect to the said passages, the said valve means comprising

- ing a stationary portion and a portion angularly adjustable with respect thereto, and gearing for connecting the said main and supplemental rotating elements together. 65
- 5 9. The combination with a casing having a main cylindrical bore therein and a plurality of supplemental cylindrical bores surrounding the central bore and in overlapping parallel relation therewith, of main and supplemental cylindrical rotating elements mounted concentrically in the said bores, and whose diameters are less than the bores containing them, the peripheries of the said main and supplemental rotating elements being in rolling contact with each other, the said main and supplemental rotating elements being provided with complementary abutments and recesses for co-engagement with each other, the sum of the diameters of all the supplemental rotating elements being equal to the diameter of the main rotating element, the said main rotating element being hollow and arranged to receive motive fluid therein, the peripheral wall thereof having a plurality of motive fluid passages therethrough one to the rear of each of the abutments therein, valve means located within the said hollow main rotating element for co-action with the said passages, means for adjusting the position of the said valve means with respect to the said passages, the said valve means comprising a stationary portion and a portion angularly adjustable with respect thereto, and gearing for connecting the said main and supplemental rotating elements together. 100
- 10 10. The combination with a casing having a main cylindrical bore therein and a plurality of supplemental cylindrical bores surrounding the central bore and in overlapping parallel relation therewith, of main and supplemental cylindrical rotating elements mounted concentrically in the said bores, and whose diameters are less than the bores containing them, the peripheries of the said main and supplemental rotating elements being in rolling contact with each other, the said main and supplemental rotating elements being provided with complementary abutments and recesses for co-engagement with each other, the sum of the diameters of all the supplemental rotating elements being equal to the diameter of the main rotating element, the said main rotating element being hollow and arranged to receive motive fluid therein, the peripheral wall thereof having a plurality of motive fluid passages therethrough one to the rear of each of the abutments therein, valve means located within the said hollow main rotating element for co-action with the said passages, means for adjusting the position of the said valve means with respect to the said passages, the said valve means comprising a stationary portion and a portion angularly adjustable with respect thereto, an automatic governing means connected with the said angularly movable portion, and gearing for connecting the said main and supplemental rotating elements together. 105
- 15 11. The combination with a casing having a main cylindrical bore therein and a plurality of supplemental cylindrical bores surrounding the central bore and in overlapping parallel relation therewith, of main and supplemental cylindrical rotating elements mounted concentrically in the said bores, and whose diameters are less than the bores containing them, the peripheries of the said main and supplemental rotating elements being in rolling contact with each other, the said main and supplemental rotating elements being provided with complementary abutments and recesses for co-engagement with each other, the sum of the diameters of all the supplemental rotating elements being equal to the diameter of the main rotating element, the said main rotating element being hollow and arranged to receive motive fluid therein, the peripheral wall thereof having a plurality of motive fluid passages therethrough one to the rear of each of the abutments therein, valve means located within the said hollow main rotating element for co-action with the said passages, means for adjusting the position of the said valve means with respect to the said passages, the said valve means comprising a stationary portion and a portion angularly adjustable with respect thereto, an automatic governing means connected with the said angularly movable portion, and gearing for connecting the said main and supplemental rotating elements together. 110
- 20 12. The combination with a casing having a main cylindrical bore therein and a plurality of supplemental cylindrical bores disposed around the same in parallel relation therewith, the said supplemental bores overlapping the said central bore whereby they are in lateral communication therewith, of a main cylindrical rotating element mounted concentrically in the said central bore, supplemental cylindrical elements mounted concentrically one in each of the said supplemental bores, the diameters of the said rotating elements being less than the bores in which they are contained and of such a size that the peripheries of the said supplemental rotating elements are in rolling contact with the periphery of the said central rotating element, the said central rotating element being provided with a plurality of abutments which extend laterally from the periphery thereof into engagement with the walls of the central bore, one for each of the said supplemental rotating elements, and with recesses for receiving the similar abut- 115
